AUTOMOTIVE DASHBOARD ILLUMINATION LAMP

Robert D. Kahn, Rockville Centre, N.Y., assignor to Fedtro, Inc., Rockville Centre, N.Y., a corporation of New York

Filed Mar. 11, 1968, Ser. No. 10,918

Term of patent 14 years

U.S. Cl. D48—32
Int. Cl. D12—14; D26—99

FIG. 1

FIG. 2

FIG. 3

FIG. 4

FIG. 5

FIG. 6

FIG. 7

FIG. 1 is a three-quartered perspective view of the automotive dashboard illumination lamp showing the front of the device;

FIG. 2 is a three-quartered perspective view showing the rear of the device;

FIG. 3 is a top plan view of the device;

FIG. 4 is a front elevational view of the device;

FIG. 5 is a bottom plan elevational view of the device;

FIG. 6 is a right side elevational view, the left side elevational view being a mirror image thereof with the switch omitted; and

FIG. 7 is a rear elevational view of the device.

I claim:

The ornamental design for an automotive dashboard illumination lamp, as shown and described.
